SHADE SUPPORTING BRACKET

Filed Jan. 17, 1930

INVENTOR
Robert Jenkins, Jr.
J. G. Dowling ATTORNEY

UNITED STATES PATENT OFFICE

ROBERT JENKINS, SR., OF BALTIMORE, MARYLAND

SHADE SUPPORTING BRACKET

Application filed January 17, 1930. Serial No. 421,331.

This invention relates to certain improvements in adjustable shade brackets and curtain pole supports, and has for its particular object the provision of an inexpensive, compact device, capable of being manufactured and sold at an extremely low cost.

A further object of the invention is the provision of a supporting bracket and curtain pole holder embodying an attaching plate capable of being easily and quickly secured to a window frame construction and the attaching plate being provided with a slidable shade supporting element and fastening means therefor, to permit the shade supporting element to be held and moved in various adjusted positions relative to the plate.

A further object of the invention is the provision of a supporting bracket and curtain pole holder, embodying an attaching plate equipped with means for holding an adjustable shade supporting bracket and provided at one end with a curtain pole support.

With these and other objects in view, the invention consists in certain novel features, combination and arrangement of parts as will be hereinafter more fully described, pointed out in the accompanying drawing, and claimed.

In the drawing,

Figure 1 is a front elevational view, illustrating my improved window shade supporting bracket, showing the method of use;

Figure 2 is a fragmentary, front elevational view of my improved shade supporting bracket, illustrating the same on a large scale to disclose its construction;

Figure 3 is a vertical sectional view, taken on the line 3—3 of Figure 2;

Figure 4 is an enlarged perspective view of the shade supporting element;

Figure 5 is a reduced perspective view of the attaching plate; and,

Figure 6 is an enlarged fragmentary sectional view, illustrating the association of the curtain pole support with the attaching plate.

Referring to the drawing, my improved invention comprises in its construction a rec-

tangular plate 6, having its opposite longitudinal edges bent back upon one face of the plate to provide guide flanges 7 and 8, respectively. The body of the plate 6 is provided with openings 9 for the reception of fastening elements 10, whereby said plate may be secured to a window frame construction "A", as clearly illustrated in Figures 1, 2, and 3, of the drawing.

The upper longitudinal edge of the plate 6, is bent back and is of a depth less than the depth of the bent back portion 8, and the terminals of these portions 7 and 8, respectively, terminate at a relatively spaced distance apart to provide a moving space for the passage of a shade supporting element.

The flange 8 is also equipped with a longitudinal slot 11, to have extended therethrough a means whereby the shade supporting element may be held in various adjusted positions relative to the plate 6.

The shade supporting element comprises a plate or body 12, provided on one of its side longitudinal edges adjacent the bottom with a lateral extension 13, having secured to one face thereof, and at right angles thereto, a screw threaded pin 14. The opposite side longitudinal edge of the plate or body 12 has a lateral extension intermediate of its ends, which is bent at right angles to the body to constitute a shade supporting member 15.

The body 12 is slidable between the flanges 7 and 8, respectively, of the plate 6. The element 15 slides between the longitudinal edges of the terminals of the flanges 7 and 8, respectively, and the pin 14 extends through the slot 11 and is equipped with a wing nut 16, so that said body 12 may be held in fixed adjusted positions relative to the plate 6.

One end of said plate 6 is bent back upon itself, as at 13'. The turned back portion of the plate 6, at the end thereof, provides an overlapping guide flange 14', having one wall open and its other wall closed, as at 15', to provide a stop 16', to limit the downward movement of the fastening end of a curtain supporting pole "C," when slidably fitted therein.

It is to be understood that the plate 6 and elements 12 are made up in pairs for the oppo-

site sides of a window frame construction, and the plates are identical in construction, so the singular term instead of the plural term has been used throughout the specification.

- 5 In use, the plates 6 are fastened to the window frames, as illustrated, the shade supporting brackets are slidably mounted between the flanges 7 and 8, respectively, of the plates 6, with the pin 14 extending
- 10 through the slot 11 of the bottom flange 8, and a wing nut 16 is fitted thereon to hold this plate in adjusted position relative to the plate 6.

The curtain pole "C" has its opposite ends slidably mounted vertically in the guide flanges 14', and the device is ready for use.

Having thus described my invention, what I claim as new is:

- 20 A combined shade supporting bracket and curtain pole support of the class described, comprising a blank stamped from a single piece of material having its opposite side longitudinal edges bent adjacent one face thereof to provide guide flanges, the longitudinal flanges of said plate terminating adjacent one another to provide a longitudinal slot, one end of said plate bent against one face thereof to provide a curtain pole support, a shade supporting element slidable on the face of said plate and located within the guide flanges, a shade supporting member extending at right angles from said element and movable in the slot defined by the flanges, and one of said flanges provided with
- 25 means to receive an associating means of the element so that the latter may be retained in adjusted positions relative to the plate.
- 30
- 35

In testimony whereof I hereunto affix my signature.

40 ROBERT JENKINS, Sr.
